DESIGN FOR A KNIFE SHARPENER

Bernard L. Chapin, Winchester, Noble L. Davis, Melrose, and Thomas H. Cabot, Jr., Boston, Mass., assignors to New England Carbide Tool Company, Inc., Cambridge, Mass., a corporation of Massachusetts

Application November 14, 1947, Serial No. 142,544

Term of patent 14 years

(Cl. D37—1)

To all whom it may concern:

Be it known that we, Bernard L. Chapin, Noble L. Davis and Thomas H. Cabot, Jr., citizens of the United States of America, and residents of Winchester, county of Middlesex, Melrose, county of Middlesex, and Boston, county of Suffolk, all in the Commonwealth of Massachusetts, respectively, have invented a new, original, and ornamental Design for Knife Sharpener, of which the following is a specification, reference being had to the accompanying drawing, forming part thereof.

In the drawing:

Fig. 1 is a view in perspective of a knife sharpener, showing our new design.

Fig. 2 is a top plan view thereof.

Fig. 3 is a side elevation thereof.

Fig. 4 is a front elevation thereof.

We claim:

The ornamental design for a knife sharpener, substantially as shown.

BERNARD L. CHAPIN.

NOBLE L. DAVIS.

THOMAS H. CABOT, JR.
